(57) **CLAIM**

The ornamental design for a fly swatter, as shown and described.

DESCRIPTION

FIG. 1 is a perspective view of a fly swatter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the bend of the fly swatter;

FIG. 10 is a perspective view thereof, showing the extension of the fly swatter; and,

FIG. 11 is an exploded perspective view of the embodiment shown in FIG. 1.

The dash-dash broken lines shown represent stitching and form part of the claimed design.
